DOOR LATCH

Ralph R. Teetor, Hagerstown, Ind.

Application December 26, 1951, Serial No. 263,227

9 Claims. (Cl. 292—64)

The invention relates generally to latches and more particularly to latches adapted for use in swinging doors.

The general object of the invention is to provide a novel door latch which is quiet in operation and does not cause any clicking sound when passing a keeper into or out of locking relation therewith.

Another object is to provide a novel door latch comprising a spring-operated catch engageable with a keeper and swingable inwardly by a camming action of the keeper on the catch to permit the catch to pass into and out of engagement with the keeper as the door is closed and opened, and a means for dampening the action of the spring as it moves the catch outwardly to prevent the latter from striking other parts of the latch with such force as would cause a noticeable sharp clicking sound.

Other objects and advantages will become apparent from the following description taken in connection with the accompanying drawing, in which:

Figure 1 is a longitudinal sectional view of a door latch embodying the features of the invention and showing the parts thereof in the position they occupy when the door is closed.

Figure 2 is a longitudinal sectional view taken on the line 2—2 of Figure 1.

Figure 3 is a fragmentary view similar to Figure 1, but showing the position of the parts as the door is being opened.

Figure 4 is a fragmentary view similar to Figures 1 and 3, but showing the position of the parts as the door is being closed.

The present invention is embodied in a latch having a movable catch member adapted to engage a keeper in the frame of a door to hold the door closed, with manually releasable means for holding the catch in engagement with the keeper. The latch also includes spring means tending to hold the catch in keeper-engaging position, with the keeper camming the catch inwardly of the door, on opening and closing thereof to pass by the keeper. The manually releasable means has no control over the catch when the spring forces it outwardly of the casing after passing by the keeper but outward movement of the catch is limited by stop means provided in the casing of the latch. After the catch has been moved inwardly of such casing in passing the keeper on opening and closing of the door, the spring means forces the catch outwardly until the catch engages such stop means.

A spring having sufficient strength to properly operate the catch in its various movements tends to force the catch outwardly of the casing, after it passes by the keeper, with sufficient force to strike sharply against the stop means and produce a clicking sound, since the manually releasable means is of a character which does not control the outward movement of the catch. Such clicking sound is undesirable in some instances. For example, if the latch is used on a bedroom door, the clicking sound might be sufficient to awaken a sleeper in the bedroom. Parents frequently wish to go into a child's bedroom

2

during the night without awakening the child, and if this clicking sound occurred, they would run that risk.

The present invention comprises a door latch of the foregoing character, but provided with means for preventing such a clicking sound when the catch is moved outwardly of the casing. To this end, dampening means is provided to dampen the action of the spring and slow down the outward movement of the catch to prevent it from striking sharply against the stop means and thus prevent making a clicking sound. Such dampening means is preferably incorporated in the spring means and insures a slow outward movement of the catch so that it will engage the stop means without impact, thus avoiding the clicking sound.

The preferred embodiment of the invention is shown in the drawing wherein the door is indicated at 10 and the door frame is shown at 11. The door frame 11 is provided with the usual stop 12 to limit the swinging movement of the door 10 in one direction. The door frame 11 is provided with a mortise 13 to receive the catch and over the face of the mortise is mounted a keeper 14 in the form of a plate having a catch-receiving opening 15 coinciding with the mortise 13.

The catch comprises a tubular casing 20 extending inwardly in a mortise in the door from the edge thereof and provided with a face plate 21 mortised in the edge of the door. Within the casing is a catch 22 which is sector shaped, having flat upper and lower faces, an arcuate face 23, and generally radial edges 24 and 25. The catch 22 is supported for movement in the casing 20 by a pair of rollers 26 located at the respective side faces of the catch 22 and rotatably secured to the catch by means of a pin 27 extending through the catch. The catch 22 is arranged to swing in opposite directions about the pin 27 upon opening and closing the door, and to move inwardly of the casing when the door is opened. When the catch is in its outward position and the door is closed, as shown in Figures 1 and 2, the arcuate edge 23 thereof engages a portion of the margin of the opening 15 in the keeper 14.

When the catch is in its outer position, bodily movement thereof is prevented by manually releasable means comprising a latch member indicated generally at 30. The latch member is mounted within the casing 20 inwardly of the catch and comprises a channel shaped part having its flange portions 31 pivotally supported in the casing by means of a cross pin 32 having its ends mounted in the walls of the casing 20 and extending through the two side flanges 31 of the latch member 30. At the outer end of the latch member, the web portion thereof is extended as at 33 to engage the pin 27 mounted in the catch and carrying the rollers 26. Thus, when the latch member 30 is swung about the cross pin 32 so that the extended portion 33 of the latch engages the pin 27, the catch is prevented from moving bodily inward of the casing. The catch is thus held in engagement with the keeper 14 to maintain the door closed.

To permit the catch to be moved bodily inward of the casing and thereby be permitted to pass by the keeper 14 to open the door, the manually releasable means is adapted to be swung about the cross pin 32 so that the extended portion 33 is swung out of engagement with the pin 27 in the catch. Thus, the latch member 30 is swung counterclockwise about the cross pin 32 from the position shown in Figure 1 to the position shown in Figure 3 where the extended portion 33 lies flat against the adjacent side of the casing 20. The pin 27 is no longer held by the extended portion 33 so that the catch may be moved bodily inward of the casing and swung about the axis of the pin 27 by a camming action of the keeper 14 on the arcuate edge 23 of the catch, as the door is forced open.

To release the latch 30 from holding engagement with the catch, the flanges 31 of the latch 30 are provided with inwardly extending portions 34 straddling a sleeve 35 extending transversely through the door. Within the sleeve 35 is a spindle 36 carrying a cross pin 37 extending through slots 40 in the sleeve 35 and engaging the inwardly extending portions 34 of the latch member 30. Thus, longitudinal movement of the spindle 36 in the sleeve 35 in a direction in which the door opens will swing the latch member 30 about its cross pin 32 to disengage the extending portion 33 thereof from the pin 27 of the catch 22.

To properly mount the spindle 36 and the sleeve 35 in the door, the sleeve extends beyond the faces of the door and is threaded at its ends to receive escutcheons 41 engaging the respective face of the door. The spindle 36 extends beyond the sleeve 35 at both ends and in the present instance I have shown knobs 42 mounted on the ends of the spindle 36 by which the latter may be moved longitudinally. Obviously, means other than the knobs 42 may be employed for operating the spindle.

As heretofore mentioned, the catch is adapted to be moved outwardly of the casing by a spring means, and its outward movement is limited by stop means. As herein shown, such stop means comprises a pair of lugs 43 formed on the respective sides of the catch 22 and adapted to engage ribs 44 in the outer end of the casing. Preferably such ribs 44 are provided by extending the face plate 21 of the casing inwardly a short distance, as shown in Figure 2. The catch 22 is also held against outward movement by engagement of the rollers 26 with an arcuate surface 45 formed on ribs 44. Thus, when the catch 22 is in its outward position, the lugs 43 as well as the rollers 26 are in engagement with the ribs 44 and outward movement of the catch is thereby limited.

The position of the parts, when the door is closed, is shown in Fig. 1, and in this figure, it will be noted that the catch 22 extends outwardly of the casing 20 and engages the margin of the opening 15 in the keeper 14. Pressure on the door in a direction to open it would tend to swing the catch 22 clockwise about the pin 27, but since the extending portion 33 is in engagement with the pin 27 and the lugs 43 are in engagement with the ribs 44, the catch 22 is held against movement in such direction. The door is therefore held closed.

To open the door, one or the other of the knobs 42 is pushed or pulled, as the case may be, in the direction of opening the door, and such movement causes the pin 37 on the spindle 36 to swing the latch member 30 about the cross pin 32 in a clockwise direction to move the extending portion 33 out of engagement with the pin 27 in the catch. Continued pressure on the door, through the camming action of the keeper 14 on the catch, causes the catch to move bodily inward of the casing and to swing in a clockwise direction about the pin 27 to the position shown in Figure 3, so that the catch 22 can pass by the keeper 14 and permit the door to swing open. After the door is thus opened and the knob is released, the spring means forces the catch outwardly of the casing, as will hereinafter be described, and also swings the latch member 30 counterclockwise to bring the extended portion 33 of the latch member into engagement with the pin 27.

When the door is swung closed, the catch 22 engages the keeper 14 and is swung counterclockwise by the camming action of the keeper to the position shown in Figure 4. During such swinging movement the extending portion 33 of the latch member remains in engagement with the pin 27 so that the movement of the catch is purely pivotal about the axis of the pin 27. The edge 25 of the catch is preferably made slightly concave so as to facilitate the camming action of the keeper on the catch. When the door is fully closed, the spring means then forces the catch outwardly of the casing until the lugs 43 engage the ribs 44, the rollers 26 being held in

engagement with the arcuate surface 45 on the ribs by the extended portion 33.

A spring means having sufficient strength to cause the catch 22 to function properly on opening and closing 5 of the door would tend to force the catch outwardly of the casing with sufficient force to cause the lugs 43 to strike the ribs 44 with considerable impact, after the catch passes by the keeper 14 on closing the door, and to cause both the lugs 43 and the rollers 26 to strike 10 the ribs 44 with considerable impact when the catch is moved outwardly of the casing after opening the door. As heretofore pointed out, such impact would cause a substantial clicking sound, which under certain circumstances would be undesirable.

One of the principal features of the present invention 15 lies in the provision of a device for preventing such clicking sound by dampening the action of the spring means in moving the catch outwardly of the casing. Structurally, such dampening device is preferably incorporated 20 in the spring means and comprises generally a piston and cylinder device which tends to compress air upon outward movement on the catch under the influence of spring means. Such air is permitted to leak slowly from the cylinder, so that the outward movement of the catch 25 is slowed down and the lugs 43 as well as the rollers 26 will be prevented from striking sharply against the ribs 44.

In the present instance, the spring means and dampening device comprises a cylinder 50 open at one end and closed at its other end by a wall 51 (see Figure 1). The 30 cylinder is pivotally supported between the flanges 31 of the latch member 30 by means of a pivot pin 52 extending through the end wall 51 and secured at its ends in upstanding portions 53 formed on the flanges 31. The end wall 51 of the cylinder is provided with a longitudinally extending sleeve 54, and within the cylinder is mounted a piston 55 having a piston rod 56 slidably mounted in the sleeve 54.

The piston rod 56 is adapted to be secured to the catch 22 and for this purpose, the piston rod 56 extends 40 beyond the sleeve 54 and is secured in a block 57 mounted in a slot 58 cut in the catch 22. The block 57 is pivotally secured to the catch by a pin 60 which is so positioned as to intersect a portion of the piston rod 56, as shown in Figure 1, and thus secure the piston rod to the block 57. Interposed between the cylinder and the catch is 45 a coiled spring 61 which bears at one end against the end wall 51 of the cylinder and at its other end against the block 57.

With the foregoing structure, it will be noted that the 50 spring resists inward movement of the catch 22 and also resists swinging movement of the latch member 30, tending to hold the latter with its extended portion 33 in engagement with the pin 27 of the catch. The spring 61, through the pressure it exerts on the latch member 30 also tends to hold the spindle 36 in proper position, ready for operation to release the catch. Thus, the spring 61 has sufficient strength, not only to shift the catch outwardly of the casing, but also to swing the latch member into engagement with the pin 27 of the catch and to shift the spindle 36 with the knobs 42. With the spring 55 of such strength, it is evident that, when moving the catch outwardly of the casing, the lugs 43 as well as the rollers 26 would be caused to engage the ribs 44 with considerable impact.

However, when the catch 22 is moved inwardly to 65 compress the spring 61, the piston 55 is moved to the left in the cylinder 50, as shown in the drawing. When the catch passes by the keeper either on opening or closing of the door, the spring forces the catch outwardly 70 of the casing and at the same time moves the piston 55 toward the end wall 51. This tends to compress air within the cylinder, but the piston has a slightly loose fit in the cylinder so that there is sufficient leakage of air around the piston 55 and along the piston rod 56 to 75 permit the spring to move the catch slowly outwardly

of the casing. The lugs 43, as well as the rollers 26, thus engage the ribs 44 without impact and no clicking sound will occur. The door latch thus will operate quietly both on opening and closing the door.

I claim:

1. A door latch comprising a casing adapted to be mounted in a door, a catch shiftably mounted in said casing and adapted to extend therefrom for engaging a keeper, manually releasable means for holding said catch in engagement with the keeper to hold the door closed, said catch being shiftable by the keeper when said means is released to open the door and being shiftable relative to said means on closing the door, a spring device opposing shifting movement of the catch both on opening and closing the door and tending to move the catch outwardly of the casing when shifted on opening or closing the door, and stop means in said casing for limiting the outward movement of the catch relative to the casing, the outward movement of the catch into engagement with said stop means after passing the keeper either on opening or closing the door being controlled solely by said spring device, said spring device including a device for dampening the action of the spring device to prevent the catch from striking said stop means with a clicking sound.

2. A door latch comprising a casing adapted to be mounted in a door, a catch shiftably mounted in said casing and adapted to extend therefrom for engaging a keeper, said catch being shiftable inwardly of the casing to pass by the keeper on opening and closing the door, a spring device opposing shifting movement of the catch both on opening and closing the door and tending to shift the catch outwardly of the casing when the catch is shifted inwardly in passing the keeper, and stop means in said casing for limiting the outward movement of the catch, the outward movement of the catch into engagement with said stop means after passing the keeper either on opening or closing the door being controlled solely by said spring device, said spring device including a device for dampening the action of the spring device to prevent the catch from making a clicking sound when engaging the stop means.

3. A door latch comprising a casing adapted to be mounted in a door, a catch shiftably mounted in said casing and adapted to extend therefrom for engaging a keeper, said catch being swingable inwardly of the casing in one direction to pass by the keeper on opening the door and in the other direction on closing the door, a spring device opposing shifting movement of the catch both on opening and closing the door and opposing inward movement of the catch when the latter swings in either direction, and stop means in the casing for limiting outward movement of the catch, the outward movement of the catch into engagement with said stop means after passing the keeper either on opening or closing the door being controlled solely by said spring device, said spring device including a device for slowing down the outward movement of the catch by the spring device to prevent the catch from striking sharply against said stop means to prevent it from making a clicking sound.

4. A door latch comprising a casing adapted to be mounted in a door, a catch shiftably mounted in said casing and adapted to extend therefrom for engaging a keeper, said catch being swingable inwardly of the casing in one direction to pass by the keeper on opening the door and in the other direction on closing the door, a spring device opposing inward movement of the catch when the latter swings in either direction, and stop means in the casing for limiting outward movement of the catch, said spring device comprising a cylinder, a piston mounted in said cylinder and having a piston rod connected to said catch, and a spring surrounding the piston rod and interposed between said cylinder and said catch and tending to force the catch outwardly of the casing, and stop means for limiting the outward movement of said catch, such outward movement causing the piston to compress air within the cylinder with the air leaking around the piston so that the catch moves slowly into engagement with said stop means to avoid making a clicking sound.

5. A door latch comprising a casing adapted to be mounted in a door, a catch shiftably mounted in said casing and adapted to extend therefrom for engaging a keeper, said catch being shiftable inwardly of the casing to pass by the keeper on opening and closing the door, a spring device opposing shifting movement of the catch both on opening and closing the door and tending to shift the catch outwardly of the casing when the catch is shifted inwardly in passing the keeper, and stop means in said casing for limiting the outward movement of the catch, said spring device comprising a spring adapted to be energized by inward movement of said catch, the outward movement of the catch into engagement with said stop means after passing the keeper either on opening or closing the door being controlled solely by said spring device, and a piston and cylinder device for slowing down the action of the spring in moving the catch outwardly of the casing so that the catch moves slowly into engagement with said stop means to avoid making a clicking sound.

6. A door latch comprising a casing adapted to be mounted in a door, a catch shiftably mounted in said casing and adapted to extend therefrom for engaging a keeper, said catch being shiftable inwardly of the casing to pass by the keeper on opening and closing the door, manually releasable means for holding the catch against inward shifting movement to open the door, a spring device opposing shifting movement of the catch both on opening and closing the door and tending to shift the catch outwardly of the casing when the catch is shifted inwardly in passing the keeper, and stop means in said casing for limiting the outward movement of the catch, said spring device comprising a spring for urging the catch outwardly of the casing and for opposing movement of said manually releasable means, the outward movement of the catch into engagement with said stop means after passing the keeper either on opening or closing the door being controlled solely by said spring device, and a dampening device for slowing down the action of the spring in moving the catch outwardly, said dampening device comprising a cylinder member and a piston member with one of said members connected to said catch and the other of said members connected to said manually releasable means.

7. A door latch comprising a casing adapted to be mounted in a door, a catch shiftably mounted in said casing and adapted to extend therefrom for engaging a keeper, said catch being shiftable inwardly of the casing to pass by the keeper on opening and closing the door, a manually operable channel shaped latch member pivotally mounted in said casing and having a portion engageable with the catch to hold the latter against inward shifting movement to open the door, a cylinder pivotally mounted between the flange portions of the channel, a piston mounted in said cylinder with a slight clearance therebetween and having a piston rod connected to said catch, a spring surrounding said piston rod and interposed between said cylinder and said catch and tending to force the catch outwardly of the casing, and stop means for limiting the outward movement of said catch, such outward movement causing the piston to compress air within the cylinder with the air leaking around the piston so that the catch moves slowly into engagement with said stop means to avoid making a clicking sound.

8. A door latch comprising a casing adapted to be mounted in a door, a catch mounted in said casing and adapted to extend therefrom for engaging a keeper, said catch being swingable inwardly of the casing in one direction to pass by the keeper on opening the door and in the other direction on closing the door, spring means connected to and opposing inward movement of the

catch when the latter swings in either direction, said casing having internal ribs adjacent its outer end on opposite sides thereof and said catch having lugs on opposite sides thereof adapted to engage said ribs and having rollers on opposite sides thereof to facilitate inward movement of the catch on opening the door, said rollers also being adapted to engage said ribs and cooperating with said lugs to limit outward movement of the catch, said spring means including a device for slowing down the outward movement of the catch by the spring means to prevent said lugs and said rollers from striking sharply against said ribs to prevent them from making a clicking sound.

9. A door latch comprising a casing adapted to be mounted in a door, a catch mounted in said casing and adapted to extend therefrom for engaging a keeper, said catch being swingable and bodily shiftable inwardly of the casing to pass by the keeper on opening the door, spring means opposing inward movement of the catch, said casing having internal ribs adjacent its outer end

5 on opposite sides thereof and said catch having rollers on opposite sides thereof to facilitate inward movement of the catch on opening the door, said rollers being adapted to engage said ribs to limit outward movement of the catch, said spring means including a device for slowing down the outward movement of the catch by the spring means to prevent said rollers from striking sharply against said ribs to prevent them from making a clicking sound.
